GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

KEY-SOCKET FOR ELECTRIC INCANDESCENT LAMPS.

969,617.

Specification of Letters Patent. Patented Sept. 6, 1910.

Application filed October 2, 1908. Serial No. 455,891.

To all whom it may concern:

Be it known that I, GILBERT W. GOODRIDGE, a citizen of the United States of America, residing in the city of Bridgeport, in the county of Fairfield, in the State of Connecticut, have invented a certain new and useful Improved Key-Socket for Electric Incandescent Lamps, of which the following is a specification.

10 The main object of my invention is to so construct a key socket for electric incandescent lamps that it will occupy the smallest possible space while supplying the requirements of standard sizes of lamps and 15 have a switch giving a breaking distance sufficient for a current of 250 volts as required by the underwriters' rules. My improved construction makes a socket especially well adapted for fixture work in which 20 the sockets have to be inclosed within ornamental husks.

In the accompanying drawings Figure 1 is a longitudinal section through my improved key socket, the outer metallic shell 25 and the insulating lining therein being indicated by dotted lines: Fig. 2 is a sectional view on the line 2—2, Fig. 1, the shell and its lining being omitted; Fig. 3 is a sectional view on the line 3—3. Fig. 4; Fig. 4 30 is a face view of the device with the screw shell removed; Fig. 5 is a perspective view of the insulation in and on which the key mechanism, terminals and contacts are mounted.

35 The insulating body A, upon which the key mechanism, contacts and terminals are mounted may be made of porcelain or other suitable material and its shape is illustrated in Fig. 5, it being there shown without any 40 of the metal parts. This insulating body A has a deep central well or chamber 5 to receive the switch mechanism, with a side slot 6 for the passage of the spindle 7 of the switch key, this slot being enlarged on its 45 outer side as shown at 8 in Fig. 5 to receive and guide the cylindrical part of the key button 9. The mouth of the well of the insulating body is preferably flared as at 10, leaving an annular surface 11 on which 50 is mounted the flanged lower end of the lamp-receiving screw shell S. The latter is secured by screws 12, and 13, Figs. 3 and 4, passing through the insulating body from the rear; and one of these screws 12 serves

at the same time to secure in a recess 15 at 55 the rear of the insulating body the terminal plate 14 with binding post 16 for one of the contact wires. The annular surface 11 at the mouth of the well is notched out or grooved at 17, and diametrically opposite 60 this notch 17 the annular surface is similarly grooved at 18 (in the case illustrated, over the slot 6 for the key spindle). In these grooves 17 and 18 is supported a contact plate 19 firmly secured to the bottom of 65 the groove 17 by a bolt and nut 20. The central part of this cross plate 19 may be enlarged in width to close up the mouth of the well, as shown in Fig. 4, and it has secured to it a button 21 against which the 70 central terminal of the lamp base may contact, but as shown in the drawing, this contact is back of the screw shell S some little distance and when the lamp is screwed in to the shell S the central contact of the lamp 75 base will project well into the mouth of the well. By this means I am enabled to make a socket three-eighths of an inch shorter than the ordinary standard socket.

So far as concerns my switch mechanism, 80 I do not restrict myself, but I prefer to use a construction similar to that shown in the Perkins Patent No. 626,927, June 13, 1899, because that switch gives a large break. This comprises an oblong switch block 40, 85 mounted with play, as usual, upon the spindle 7 of the key and co-operating with a contact plate 24, (Fig. 2), secured in the bottom of the well 5 of the insulating body and provided with a binding post 29 at the 90 open side of the insulating body through which the plate 24 projects, (Fig. 2). This switch block 40 is confined between plates 32 carried by the contact plate 19 and is acted on by a spiral spring 37 between the cross 95 plate 19 and a disk 36 guided to slide on the plate 32, as in the Perkins construction.

I claim as my invention—

1. An electric lamp key socket, with a chambered insulating body, a switch mechanism therein, a screw shell mounted on the insulating body to form a lamp-receiving terminal and a central contact plate back of the screw shell in combination with co-operating switch mechanism, carried by the 100 contact plate.

2. An electric lamp key socket, having an insulating body with a well to receive the 105

switch mechanism, a screw shell forming one of the lamp terminals, mounted on the insulating body, at the mouth of the well, and a central contact plate projecting across

shoulder, and a contact plate mounted in said notches and back of the screw shell in combination with coöperating switch mechanism. 15

5 the mouth of the well back of the said screw shell in combination with coöperating switch mechanism, carried by the contact plate.

3. An electric lamp key socket, having a chambered insulating body with a well for 10 the switch mechanism, an annular shoulder at the mouth of the well to receive the screw shell terminal, notches in said annular

In testimony whereof I have signed my name to this specification, in the presence of two subscribing witnesses.

GILBERT W. GOODRIDGE.
